COMBINED ASH TRAY AND COASTER

John F. Bonistall, Zanesville, Ohio

Application November 13, 1956, Serial No. 43,739

Term of patent 7 years

(Cl. D85—2)

FIG. 1

FIG. 3

Fig. 1 is a perspective view of a combined ash tray and coaster showing my new design;

Fig. 2 is a cross-sectional view taken on the line 2—2 of Fig. 1; and

Fig. 3 is a bottom plan view thereof.

The dominant feature of the invention resides in the portion shown in full lines.

I claim:

The ornamental design for a combined ash tray and coaster, as shown and described.
